CLAIM

The ornamental design for a buckle, as shown and described.

DESCRIPTION

FIG. 1 is a front perspective view of a buckle having a base and a latch.

FIG. 2 is a rear perspective view of the buckle of FIG. 1.

FIG. 3 is a front view of the buckle of FIG. 1.

FIG. 4 is a rear view of the buckle of FIG. 1.

FIG. 5 is a left side view of the buckle of FIG. 1.

FIG. 6 is a right side view of the buckle of FIG. 1.

FIG. 7 is a top view of the buckle of FIG. 1.

FIG. 8 is a bottom view of the buckle of FIG. 1.

FIG. 9 is a front perspective view of the base of the buckle of FIGS. 1-8.

FIG. 10 is a rear perspective view of the base of FIG. 9.

FIG. 11 a front view of the base of FIG. 9.

FIG. 12 is a rear view of the base of FIG. 9.

FIG. 13 is a left side view of the base of FIG. 9.

FIG. 14 is a right side view of the base of FIG. 9.

FIG. 15 is a top view of the base of FIG. 9.

FIG. 16 is a bottom view of the base of FIG. 9.

FIG. 17 is a front perspective view of the latch of the buckle of FIGS. 1-8.

FIG. 18 is a rear perspective view of the latch of FIG. 17.

FIG. 19 is a front view of the latch of FIG. 17.

FIG. 20 is a rear view of the latch of FIG. 17.

FIG. 21 is a left side view of the latch of FIG. 17.

FIG. 22 is a right side view of the latch of FIG. 17.

FIG. 23 is a top view of the latch of FIG. 17.

FIG. 24 is a bottom view of the latch of FIG. 17.

FIG. 25 is a partial environmental view of the buckle of FIGS. 1-8, illustrating the buckle of FIGS. 1-8 securing straps of a helmet, with the partial view of the helmet and straps in broken lines.

FIG. 26 is a front perspective view of another buckle having a base and a latch.

FIG. 27 is a rear perspective view of the buckle of FIG. 26.

FIG. 28 is a front view of the buckle of FIG. 26.

FIG. 29 is a rear view of the buckle of FIG. 26.

FIG. 30 is a left side view of the buckle of FIG. 26.

FIG. 31 is a right side view of the buckle of FIG. 26.

FIG. 32 is a top view of the buckle of FIG. 26.

FIG. 33 is a bottom view of the buckle of FIG. 26.

FIG. 34 is a front perspective view of the base of the buckle of FIGS. 26-33.

FIG. 35 is a rear perspective view of the base of FIG. 34.

FIG. 36 a front view of the base of FIG. 34.

FIG. 37 is a rear view of the base of FIG. 34.

FIG. 38 is a left side view of the base of FIG. 34.

FIG. 39 is a right side view of the base of FIG. 34.

FIG. 40 is a top view of the base of FIG. 34.

FIG. 41 is a bottom view of the base of FIG. 34.

FIG. 42 is a front perspective view of the latch of the buckle of FIGS. 26-33.

FIG. 43 is a rear perspective view of the latch of FIG. 42.

FIG. 44 is a front view of the latch of FIG. 42.

FIG. 45 is a rear view of the latch of FIG. 42.

FIG. 46 is a left side view of the latch of FIG. 42.

FIG. 47 is a right side view of the latch of FIG. 42.

FIG. 48 is a top view of the latch of FIG. 42.

FIG. 49 is a bottom view of the latch of FIG. 42.

FIG. 50 is a partial environmental view of the buckle of FIGS. 26-33, illustrating the buckle of FIGS. 26-33 securing straps of a helmet, with the partial view of the helmet and straps in broken lines.

FIG. 51 is a front perspective view of another buckle having a base and a latch.

FIG. 52 is a rear perspective view of the buckle of FIG. 51.

FIG. 53 is a front view of the buckle of FIG. 51.

FIG. 54 is a rear view of the buckle of FIG. 51.

FIG. 55 is a left side view of the buckle of FIG. 51.

FIG. 56 is a right side view of the buckle of FIG. 51.

FIG. 57 is a top view of the buckle of FIG. 51.

FIG. 58 is a bottom view of the buckle of FIG. 51.

FIG. 59 is a front perspective view of the base of the buckle of FIGS. 51-58.

FIG. 60 is a rear perspective view of the base of FIG. 59.

FIG. 61 a front view of the base of FIG. 59.

FIG. 62 is a rear view of the base of FIG. 59.

FIG. 63 is a left side view of the base of FIG. 59.

FIG. 64 is a right side view of the base of FIG. 59.

FIG. 65 is a top view of the base of FIG. 59.

FIG. 66 is a bottom view of the base of FIG. 59.

FIG. 67 is a front perspective view of the latch of the buckle of FIGS. 51-58.

FIG. 68 is a rear perspective view of the latch of FIG. 67.

FIG. 69 is a front view of the latch of FIG. 67.

FIG. 70 is a rear view of the latch of FIG. 67.

FIG. 71 is a left side view of the latch of FIG. 67.

FIG. 72 is a right side view of the latch of FIG. 67.

FIG. 73 is a top view of the latch of FIG. 67.

FIG. 74 is a bottom view of the latch of FIG. 67; and,

FIG. 75 is a partial environmental view of the buckle of FIGS. 51-58, illustrating the buckle of FIGS. 51-58 securing straps of a helmet, with the partial view of the helmet and straps in broken lines.

The broken lines depict portions of the buckle that form no part of the claimed design. The broken lines immediately adjacent to the shaded areas define the bounds of the claimed design and form no part thereof.
